UNITED STATES PATENT OFFICE

2,186,695

DRAFTING UNIT

Thomas Harris, Providence, R. I., assignor to
 Harris Textile Machinery Corporation, a corporation of Rhode Island

Application February 26, 1937, Serial No. 127,890

3 Claims. (Cl. 19—141)

This invention relates to a drafting unit such as is shown in my Patent #1,922,949, and has for one of its objects the provision of an improved roll mounting which will minimize the collecting 5 of lint or other foreign material, attendant the drafting operation.

Another object of the invention is the provision of a mounting for a drafting roll in which the portion extending axially beyond the end of the 10 roll does not rotate to cause a collection of lint or fibers which may drop inwardly along the edge of the roll.

Another object of the invention is the providing 15 of a mounting for a spinning roll which will maintain the roll in position against axial shifting, shifting being governed purely by any transverse motion which is given by the mounting of the roll.

Another object of the invention is the provision 20 of a mounting which may be readily replenished or a new mounting substituted and yet one which is of simple construction and easily positionable in the mechanism.

With these and other objects in view, the invention 25 consists of certain novel features of construction, as will be more fully described, and particularly pointed out in the appended claims.

In the accompanying drawing:

Fig. 1 is a top plan view of a unit in which 30 both rolls are equipped with the improved mounting;

Fig. 2 is a sectional view on line 2—2 of Fig. 1;

Fig. 3 is a sectional view on line 3—3 of Fig. 1;

Fig. 4 is a sectional view through one of the 35 rolls and its mounting;

Fig. 5 is a sectional view through the roll shown in Fig. 4 with the bushings and axle upon which it is mounted removed;

Fig. 6 is a perspective view of the mounting pin 40 which is shown in Fig. 4;

Fig. 7 is a perspective view of one of the bushings shown in Fig. 4;

Fig. 8 is a perspective view of the spring ring which locks the pin of Fig. 6 in place;

Fig. 9 is a perspective view of the mounting member for the roll shown in Fig. 3.

In the use of spinning units such as illustrated in my Patent #1,922,949 when some sorts of work are passing through the machine where the fly 50 or lint from the work is prevalent, this lint will drop in between the roll and its mounting and where this lint contacts a moving point will cause an accumulation to be built up and in order to avoid this accumulation of material I have provided that the support for the roll be stationary

so that any lint dropping upon this support will not be wound up to enhance its accumulation in the device. The mounting for one of the rolls requires a driving connection with the roll whereas the mounting for the other roll requires no such driving connection, and accordingly I have caused the mounting for the drive and the driven rolls to be somewhat different although both embody the same general underlying thought and principle, and the following is a more detailed description of the present embodiment of this invention, illustrating the preferred means by which these advantageous results may be accomplished:

With reference to the drawing, Figs. 2, 4, 5, 6, 7, 15 and 8 relate to the driven roll which is designated 10 and is illustrated as being of metal with a fluted working surface 11, and end surfaces designated generally 12, which have a step formation 13 providing a narrower working face 11 than the bearing portion 14 adjacent the axis. There is also provided an axial bore 15 into which there are forced bushings 16 from the opposite ends 12, these bushings fitting tightly within the bore and leaving a space 17 between them into which there fits a spring ring 18. A pin 19 extends through these bushings and is rotatably mounted therein, this pin being provided with an annular groove 20 which receives the spring ring 18 to lock this pin against axial movement.

The pin 19 is provided with flat portions 21 on opposite sides of each end which are received within the slot 22 in a carriage 23 in the unit designated generally 24. This carriage 23 is urged by means of a spring 25 about a pivot 26 to move the driven roll 10 toward the drive roll 28. It will thus be seen that the pin 19 extends from a point inwardly of the roll 10 to a point outwardly thereof and that this pin is non-rotatable so that any lint dropping inwardly along the end surfaces 12 of the roll will not be wound up to mat and excessively accumulate thereon.

The drive roll 28 is provided with a fluted working surface 29 and end surfaces 30 which are recessed as at 33 concentric with the axial bore 32. A shaft 34 is corrugated as at 50 and has a driven fit with the bore 32 so as to fixedly mount the roll 28 upon this shaft 34. Bearing members designated generally 35 shown in perspective in Fig. 9 are provided with flange portions 36 to fit within the recesses 33 and provide a bearing for the roll. Formed integral with each of the flanges 36 is a rectangular body portion 37 which is received within a correspondingly shaped socket of a mounting member 38 in the unit 24 and is

held against rotation in this mounting. Each member 35 is also provided with a bore 39 to receive and provide a bearing for the shaft 34 on either side as it extends beyond the roll 28. This shaft is driven through the worm gear 40 which is fixed upon the smaller portion 41 of the shaft 34, and the worm 42 mounted in the unit 24 and driven in a desired manner.

From the above it will be apparent that any lint 10 dropping along the end surface of the roll 28 will engage the non-rotatable bearing 35 and be prevented from being wound up, matted and excessively accumulated, this bearing extending from a point inwardly from the end surface to a point 15 outwardly therefrom for this purpose.

The foregoing description is directed solely toward the construction illustrated, but I desire it to be understood that I reserve the privilege of resorting to all the mechanical changes to which 20 the device is susceptible, the invention being defined and limited only by the terms of the appended claims.

I claim:

1. In a spinning unit, a spinning roll, an axle 25 fixed thereto to rotate therewith, said roll having recesses in its opposite ends with bearing surfaces having the axis of the roll as a center, non-rotatable members in said recesses having a loose fit on said axle providing a bearing for the roll

and also having a bore providing a bearing for the axle fixed to said roll, and means on said axle for driving the same.

2. In a spinning unit, a spinning roll, an axle 5 fixed thereto to rotate therewith, said roll having recesses in its opposite ends with bearing surfaces having the axis of the roll as a center, non-rotatable members having a loose fit on said axle and each provided with a bore forming a bearing for the axle and provided with a flange to extend 10 into said recesses and provide a bearing for the roll, and means on said axle for driving the same.

3. In a spinning unit, a short hollow spinning roll, an axle fixed thereto to rotate therewith, 15 said axle being of greater length than the roll to provide axle extensions at each side thereof, said roll having recesses in its opposite ends with bearing surfaces having the axis of the roll as a center, non-rotatable members having a loose fit 20 on said axle and each provided with a bore forming a bearing for the axle extensions and provided with a flange to extend into said recesses and provide a bearing for the roll, and means on said axle for driving the same, said flange being thick- 25 er than the depth of said recess and protruding outwardly beyond the end of the roll.

THOMAS HARRIS.
